(57) **CLAIM**

The ornamental design for a wet sheet dispenser, as shown and described.

DESCRIPTION

The patent or application file contains at least one drawing executed in color. Copies of this patent or patent application publication with color drawing(s) will be provided by the Office upon request and payment of the necessary fee.

1. Wet sheet dispenser
- 1.1 : Top Perspective
- 1.2 : Bottom Perspective
- 1.3 : Front
- 1.4 : Back
- 1.5 : Top
- 1.6 : Bottom
- 1.7 : Left
- 1.8 : Right

The area shown in red illustrates portions of the wet sheet dispenser that form no part of the claimed design.

1 Claim, 8 Drawing Sheets
(3 of 8 Drawing Sheet(s) Filed in Color)
